UNITED STATES PATENT OFFICE.

HENRY T. WINDT, OF TORONTO, ONTARIO, CANADA.

CARPET-FASTENER.

SPECIFICATION forming part of Letters Patent No. 340,902, dated April 27, 1886.

Application filed January 11, 1886. Serial No. 188,171. (No model.) Patented in Canada April 30, 1884, No. 19,254.

To all whom it may concern:

Be it known that I, HENRY THEODORE WINDT, of the city of Toronto, in the county of York, in the Province of Ontario, Canada, have invented certain new and useful Improvements in Mat-Fasteners, of which the following is a specification.

The invention relates to, and consists in, the peculiar combinations, construction, and arrangement of parts, as more fully hereinafter described, and then specifically pointed out in the claims.

In the accompanying drawings, which form a part of this specification, Figure 1 shows in perspective the stationary part of the mat-fastener. Fig. 2 is a similar view of a movable part. Fig. 3 shows an end view of my improvements applied to a mat.

Referring to the drawings by letter, A designates a bracket provided with base *a*, having a plurality of holes, *a'*, to receive the screws or other means of securing it in the desired position. The vertical portion *B* of this bracket is provided with a lip, *b*, designed to overlie the edge of the mat, as will be readily understood. When in connection with my improved wire mat described in my application of even date herewith, the last row of scrapers fit under this lip and are securely held in place thereby.

These brackets *A* are designed to be made in lengths from which the brackets of the desired size may be cut when required.

These brackets are designed to be used as follows: When the bracket is used to hold the mat in position against the riser of a step or against the wall, but one bracket will be required; but where the mat is located away from the riser or wall—as, for instance, in the middle of the floor or a step—two of these brackets will be used—one upon each side of

the mat. If these brackets *A* are used on both sides of the mat, the latter may be slipped in from the end, or by bending it so as to arch it up in the middle it will readily slip under the edges of the lip; but in order to allow of the more easy removal of the mat for the purpose of sweeping beneath it or otherwise, I provide the movable bracket *C*, having a lip, *c*, similar to the lip *b* of the bracket *A*, which bracket is designed to be used instead of one of the brackets *A*. This bracket *C* is hinged at *d*, and is provided with a locking head or stud which, when turned in one direction, fits into and is coincident with a slot, *e*, in the upper hinged half of the bracket *C*, thereby permitting it to be freely opened; but when the bracket is to be locked down for the purpose of securing the mat in position, the head *E* is turned so as to be at right angles to the length of the slot, so as to overlap the edges thereof, as shown in Fig. 2. By this construction I provide brackets that are cheap, durable, and most efficient for the purpose for which they are designed.

What I claim as my invention is—

1. The combination, with the bracket *A*, having lip *b*, to engage the edge of a mat, of the hinged bracket *C*, provided with lip *c*, and a locking-stud, *E*, substantially as and for the purpose specified.

2. The bracket *C*, having lip *c*, to engage the edge of a mat, and hinged at *d*, the upper half of said bracket being provided with elongated slot *e*, and the lower half with a locking-head, *E*, designed to engage said slot, substantially as and for the purposes specified.

Toronto, January 4, 1886.

HENRY T. WINDT.

In presence of—

CHARLES C. BALDWIN,
J. M. JACKSON.
